BATTERY POWERED TAPE RECORDER

Eugene J. Freeman, Studio City, Calif., assignor to Freeman Electronics Corporation, Los Angeles, Calif., a corporation of California

Filed June 3, 1963, Ser. No. 75,170

Term of patent 14 years

(Cl. D26—14)

FIG. 1 is a front, top and right side perspective view of a battery powered tape recorder, showing my new design.

FIG. 2 is a top plan view thereof.

FIG. 3 is a left side elevational view thereof.

The grille covering is conventional and continuous over the front surface. A portion of each of FIGS. 1 and 2 is diagonally lined to indicate transparency. The dominant features of my new design are shown in solid lines in the drawing.

I claim:

The ornamental design for a battery powered tape recorder, as shown and described.
